UNITED STATES PATENT OFFICE.

HENRY WOLCOTT, OF PROVIDENCE, RHODE ISLAND.

INTERCHANGEABLE LINKS FOR CHAINS AND BRACELETS.

1,159,311.

Specification of Letters Patent.

Patented Nov. 2, 1915.

Application filed June 21, 1915. Serial No. 35,221.

To all whom it may concern:

Be it known that I, HENRY WOLCOTT, a citizen of the United States, residing at Providence, in the county of Providence and State of Rhode Island, have invented certain new and useful Improvements in Interchangeable Links for Chains and Bracelets, of which the following is a specification.

10 My present invention relates to improvements in the construction of interchangeable tubular link sections, and hinge members for detachably connecting the sections, and having the structure arranged to form a plurality of link units of a chain or bracelet for ladies' wear.

In the accompanying drawings, Figure 1 is a perspective view of one of the hollow link sections itself; Fig. 2 is a perspective 20 view of the hinge member constructed to connect a pair of said hollow sections; Fig. 3 represents the blanks from which the hinge is made before they are folded and jointed together; Fig. 4 is a side elevation of a complete link unit, viewed from its inner or reverse side; Fig. 5 is a horizontal sectional view, enlarged, taken on line 5—5 of Fig. 4; Fig. 6 is a front elevation of a plurality of the connected link units embodying my improvement, showing means for clasping or interlocking the ends of the chain to produce a band or bracelet; and Fig. 7 represents the end links when clasped together.

In the construction of my improved chain, 35 the hollow section members a are each formed from a relatively short piece cut from a length of seamless drawn tubular wire stock having a suitable cross-section. The ends of the section member are formed 40 at right angles with its upper and lower edges, and provided on what may be called the inner or reverse face x (Fig. 1) with alining apertures a^1 , each aperture adapted to receive the catch m of the spring tongue t 45 of the corresponding hinge member. The walls of the sections a are or may be uniform in thickness throughout, the shape longitudinally being straight or slightly arcuate, as desired. The form of the member a 50 cross-sectionally is preferably rectangular.

The hinge or joint member d consists of a pair of blanks b , b^1 (Fig. 3) cut from suitable sheet stock. Each blank is folded back flatwise on itself to form wings, the free 55 ends being slightly separated to produce a yielding pressure in inserting the wings

into the corresponding open ends of the sections a . The width of the wing portions w , w^1 of the hinge member is the same as the outer width of the section itself, less the thickness of the upper and lower walls of the latter. One of the blanks, b^1 , at the center of the hinge is flush with the upper and lower edges of the section member; the end portions of the walls may be recessed 60 or concaved (see r , Fig. 1) so as to permit the folded blank b^1 to swing freely at that point. The hinge blanks are formed with a central eye or loop through which a connecting joint wire e extends, the metal being pressed snugly against the wire, thereby producing a fast joint; at the same time the eye of the other folded blank or wing w^1 permits the wire to swing freely therein, as in flexing. Each of the flat wing members of the hinge is cut or incised through 70 its inner leaf or fold to form a spring-like tongue t , its free end, adjacent the hinge eye, being bent outward at right angles and forming a short catch or lug m arranged to 75 spring into the registering aperture a^1 of the section, thereby locking the members together against accidental separation; the said catch does not project through the wall 80 of the section, consequently the wearer is 85 not subjected to inconvenience or annoyance thereby. It will be seen that the chain presents a smooth and neat appearance and forms an attractive, strong and durable article of jewelry. It may be added that the 90 act of inserting the respective wings into the ends of the sections causes the spring tongue thereof to be retracted until the lug or catch m registers with the corresponding aperture, at which instant the catch automatically springs into the aperture to hold 95 the parts in the normally locked position.

I would state that in my present invention a complete unit consists of a pair of hollow sections or members a and an intermediate 100 hinge element adapted to detachably connect the said sections together. As thus constructed, the units are interchangeable and capable of being readily attached to or detached from the chain, as desired. The outer or obverse surface x^1 of each hollow section of the chain may be suitably ornamented or engraved, or the sections may bear the initials of the respective donors.

In case it is desired to convert the connected chain links into an endless band, as for example, a bracelet, the terminal links 110

may be provided with a self-locking catch, substantially as represented in Fig. 7, wherein in the catch member *c* is jointed to the said member *w* of the normal hinge in lieu of the other member *w*¹. In this construction and arrangement the free end of the corresponding terminal link or hollow section A is adapted to receive the catch *c*, the upper arm of the latter being resilient and provided 10 with the pusher and locking projections *h*, *h*¹, respectively. The upper wall of the link A is provided with an open slot *s* to receive the pusher *h*, and is also provided with a hole *f* into which the locking lug *h*¹ extends 15 when the band is closed. The lug *h*¹ is beveled to facilitate its entrance into the hole *f*. To unlock or unclasp the band downward pressure is applied to the pusher *h*.

20 I claim:—

1. An interchangeable link-unit for links of chains or bracelets and the like, said link-unit comprising a pair of main hollow section members formed of seamless drawn 25 metal tube, the said section members being substantially uniform in character throughout, each hollow section having an opening in its wall adapted to receive a catch or lock-

ing member, and a hinge element intermediate of and connecting a pair of the main 30 sections, said hinge element having resilient catches integral therewith adapted to automatically spring into the said openings of the respective sections to detachably connect the contiguous sections of the link-unit. 35

2. In a chain or bracelet and the like of the general character described having main hollow section members detachably connected together by intermediate hinge elements, the combination with a longitudinal 40 hollow end section having an aperture in its side wall, of a hinge, a member of said hinge provided with a catch adapted to spring into said aperture, a longitudinal fellow hollow end section having an opening 45 in its wall, a laterally movable wing member jointed to said hinge adapted to enter the free end of the last-named hollow end section, and clasping means integral with said laterally movable wing member of the hinge 50 engageable with the opening of the last-named end section, for detachably connecting the ends of the band together.

In testimony whereof I have affixed my signature.

HENRY WOLCOTT.
